UNITED STATES PATENT OFFICE.

VALENTINE STREIT, OF ALVORD, IOWA.

INVALID-LIFTER.

1,252,859.

Specification of Letters Patent. Patented Jan. 8, 1918.

Application filed April 7, 1917. Serial No. 160,511.

To all whom it may concern:

Be it known that I, VALENTINE STREIT, a citizen of the United States, residing at Alvord, in the county of Lyon and State of Iowa, have invented certain new and useful Improvements in Invalid-Lifters, of which the following is a specification, reference being had to the accompanying drawings.

10 This invention relates to certain improvements in invalid lifters and it is an object of the invention to provide a novel and improved device of this general character whereby the invalid may be positioned upon the device with convenience and facility.

15 It is also an object of the invention to provide a device of this general character having novel and improved means whereby the same may be readily employed as a reclining chair.

20 The invention consists in the details of construction and in the combination and arrangement of the several parts of my improved lifter whereby certain important advantages are attained and the device is rendered simpler, less expensive and otherwise, more convenient and advantageous for use, all as will be hereinafter more fully set forth.

25 The novel features of the invention will hereinafter be definitely claimed.

30 In order that my invention may be the better understood, I will now proceed to describe the same with reference to the accompanying drawings, wherein—

35 Figure 1 is a view in side elevation of a lifter constructed in accordance with an embodiment of my invention and in assembled relation for use as a reclining chair or the like;

40 Fig. 2 is a view in top plan of the device in assembled relation for lifting a person, certain of the parts being broken away to illustrate details of construction;

45 Fig. 3 is a view in elevation of a supporting member as herein employed;

50 Fig. 4 is a longitudinal vertical sectional view taken through the device as illustrated in Fig. 1;

55 Fig. 5 is a view in top plan of the device as disclosed in Fig. 1; and

Fig. 6 is a view in perspective of a second supporting member as herein set forth.

As herein disclosed, my improved device comprises two elongated flat members M, the opposed longitudinal edges of said mem-

bers being substantially in contact one with the other when in assembled relation. Each of the members M comprises a plurality of sections 1, 2 and 3 having their adjacent ends pivotally or hingedly connected, as indicated at 4. The outer ends of the sections 1 and 3 of each of the members M are provided with the outstanding pins or dowels 5. Each of the pins or dowels 5 is adapted to be inserted within an opening 6 formed in the inner edge of the head piece 7 and the foot piece 8.

When it is desired to lift a patient from a bed a member M is arranged beneath the patient from one side and the second member M arranged therebeneath from the opposite side. The head piece 7 and foot piece 8 are then engaged with the members M and serve to hold said members M in the requisite assemblage. The patient can then be readily removed. After the members M containing the patient have been removed from the bed the foot piece 8 is adapted to be engaged with the support S.

55 As herein disclosed, the support S comprises a pedestal 9 adapted to have its upper edge extend beneath the foot piece 8 substantially at the longitudinal center thereof. The outer vertical margin of the pedestal 9 is defined by the upstanding extension 10 to overlie the outer face of the foot piece 8, as is particularly illustrated in Figs. 1 and 4. A pin 11 is then disposed through the extension 10 and inserted within the foot piece 8.

60 The inner vertical marginal portion of the pedestal 9 at the upper end thereof is provided with the cross piece 12 which extends beyond opposite sides of the pedestal 9 and underlies the outer end portions of the sections 3 of the members M. It is preferred that the patient when being lifted from the bed assume a sitting posture and this is permitted by swinging the sections 1 and the head piece 7.

65 The pivoted portions of the sections 1 and 3 of the members M are adapted to be rested upon the shelf 14 extending inwardly from the head support H. The support H comprises a member or plate 15 preferably rectangular in form and of a width in excess of the width of the assembled sections M. The marginal portions of the member or plate 15 and the shelf 14 are reinforced by the side brace members 16 triangular in form with their apices inwardly directed.

Pivots engaged with the outer edge of each of the members 1 adjacent the free ends thereof are the rigid brace arms 17 adapted to detachably engage with a laterally directed pin 18 carried by an intermediate section 2 of a member M whereby the section 1 is effectively locked in its lifted or elevated position.

Secured to the outer face of each of the 10 brace members 16 is a flexible member 19 which is adapted to be tied or otherwise secured to a head member 20 or the like, extending outwardly from an end of the cross member 12. By this arrangement it will 15 be at once self-evident that the device may be readily locked in assembled relation when the device is arranged on the supports S and H.

I also find it of advantage to employ the 20 tray T so that the patient may be served. As herein embodied, the tray T includes the table 21 provided at its opposite end portions with the depending wings 22. The lower end of each of the wings 22 is provided with a shoulder 23 adapted to rest upon the upper edge of a brace 17 when the same is in applied position, while the inner end portion of said wing 22 is arranged on a suitable incline, as indicated at 24, to rest 25 upon the upper edge of the adjacent brace member 16. It is also to be noted that the inner end portion of the wing 22 overlies the outer face of the adjacent brace arm 17. When the table T is in applied position the 30 lower ends of the shoulders 23 contact with the upper faces of the sections 2 of the assembled members M whereby said table is prevented from sliding down the brace arms 17. The wings 22 also engage the brace arm 17 with sufficient friction to prevent the table T from tipping forward under the influence of the weight imposed thereupon by the dishes and the contents thereof when it is desired to feed a patient.

45 As disclosed in the accompanying drawings or more particularly Figs. 1, 4 and 5, the members M are shown in a position whereby the limbs of the patient are maintained elevated. If desired, however, the 50 device may be converted into a chair by removing the foot piece 8 and permitting the sections 3 of the members M to drop. With this arrangement it is to be understood that a suitable support will be disposed beneath 55 the intermediate sections 2 of the members M.

From the foregoing description, it is thought to be obvious that a lifter constructed in accordance with my invention is of an 60 extremely simple and comparatively inexpensive nature and is particularly well adapted for use by reason of the convenience and facility with which it may be assembled, and it will also be obvious that my invention 65 is susceptible of some change and modi-

fication without material departure from the principles and spirit thereof and for this reason I do not wish to be understood as limiting myself to the precise arrangement and formation of the several parts herein shown in carrying out my invention in practice, except as hereinafter claimed.

I claim:

1. An invalid lifter comprising two elongated separable members arranged side by side and having their adjacent longitudinal margins in contact, and means co-acting with the ends of said members for maintaining the members in assembled relation.

2. An invalid lifter comprising two elongated separable flat members, the opposed longitudinal edges of said members being substantially in contact one with the other when in assembled relation, the opposite ends of said members being provided with outstanding pins, a head piece provided with recesses to receive the pins and corresponding ends of the elongated members, and a foot piece provided with recesses to receive the pins at the opposite ends of said elongated members.

3. An invalid lifter comprising two elongated separable flat members, the opposed longitudinal edges of said members being substantially in contact one with the other when in assembled relation, the opposite ends of said members being provided with outstanding pins, a head piece provided with recesses to receive the pins and corresponding ends of the elongated members, a foot piece provided with recesses to receive the pins at the opposite ends of said elongated members, each of said elongated members comprising pivotally connected sections, and a brace member co-acting with adjacent pivoted sections of each of the members for maintaining the same in angular relation.

4. An invalid lifter comprising two elongated separable flat members having adjacent longitudinal edges in contact when in assembled relation, a support detachably engaged with corresponding end portions of the elongated member, a cross member detachably engaged with the opposite end portions of the first named elongated members, said second support comprising a pedestal having its upper edge underlying the cross member and disposed longitudinally of the first named elongated members, and a cross piece carried by the upper portion of the pedestal and extending transversely of the first named elongated members and underlying and contacting with the cross member and the adjacent end portions of the two elongated members.

5. An invalid lifter comprising two elongated separable flat members having adjacent longitudinal edges in contact when in assembled relation, a support detachably engaged with corresponding end portions of

- the elongated member, a cross member detachably engaged with the opposite end portions of the first named elongated members, said second support comprising a pedestal 5 having its upper edge underlying the cross member and disposed longitudinally of the first named elongated members, a cross piece carried by the upper portion of the pedestal and extending transversely of the first 10 named elongated members and underlying and contacting with the cross member and the adjacent end portions of the two elongated members, an upstanding extension carried by the cross piece and overlying the adjacent face of the cross piece, and means for 15 securing said extension to the cross member.
6. A device of the character described comprising two elongated separable members having adjacent longitudinal edges in contact in assembled relation, each of said 20 members comprising three pivotally connected sections, the end sections of each of the members being movable in opposite directions, and means co-acting with the opposite ends of the elongated members for maintaining the same in assembled relation. 25

In testimony whereof I hereunto affix my signature in the presence of two witnesses.

VALENTINE STREIT.
